SPARK PLUG CLEANER

Charles B. McPherson, Birmingham, Ala.

Application August 26, 1944, Serial No. 551,318

1 Claim. (Cl. 51—8)

This invention relates to a spark plug cleaner and has for its main objects to provide a device of this character which will be small so as to be part of the tool equipment of an automobile, highly efficient, cheap to manufacture, easy to operate, and simple in structure. It may be used from a compressed air source where the same is available, or with air from an ordinary hand tire pump. Other advantages will appear from the description.

The device employs the sand blast system in a small way. This system in a large and expensive way is used in well established automobile service stations.

Referring to the drawing, part of this application, it will be observed that Fig. 1 is a center sectional view of the assembled cleaner with a spark plug inserted in place for cleaning; and Fig. 2 is a partial view showing the operating end of a cleaner with a spark plug disconnected from the place for cleaning.

Similar reference numerals refer to similar parts throughout the views.

Again referring to the drawing in detail it will be seen that the device comprises a pear shaped outer frame 5 or bracket that is attached at its small end to a piece of tubing 3 that is provided with a threaded hole 11 into which a regular spark plug 1 with threads 2 is set or screwed in for cleaning. A suitable cloth bag 4 of a shape simulating a pear and not airtight has its small end tightly fit around the tube 3. The large end of the bag is held between jam nuts 7—8 that are carried on a threaded portion of an air tube 6 that extends from outside and through the large end of the bracket 5 and down to near the bottom of the tube 3. A small amount of sand or other abrasive material 10 is put into the bag through the spark plug hole while holding the device with the hole at the top. Compressed air from a source (not shown) enters through a flexible tube 9 attached to the outer end of air tube 6. The spark plug is also shown in its disconnected position 1—a, 2—a.

To use the device the spark plug 1 is screwed into the threaded hole 11 with hole at top, then the cleaner is reversed with the hole in bottom position, then air is forced in through the air tube 6 and agitates the sand that has settled in the bottom of the tube 3 and spark plug recess. The agitation of the sand cuts the carbon accumulation off of and out of the spark plug. Then the cleaner is reversed to put the spark plug at the top so as it may be removed without allowing the sand to fall out of the bag. When sand becomes dirty it is replaced with clean sand.

The various parts of the cleaner may be made from any material best suited for the purpose.

While I have shown and described the preferred embodiment of my invention I do not wish to limit same to the exact and precise details of structure, but reserve the right to make all changes and modifications so long as I remain within the spirit and scope of the following claim.

Having described my invention I claim:

A portable spark plug cleaner of the class described comprising a metal band frame, said frame being larger at one end than the other, a short piece of tubing attached to the small end of said frame, a non-airtight cloth bag of a shape substantially like a pear contained within said frame by means of jam nuts clamping its large end to said frame and its small end adapted to fit tight around the inner end of said tubing, the outer end of said tubing having a threaded hole adapted to fit the screw portion of a spark plug, an air tube entering the large end of said frame and the large end of said bag, said air tube having a threaded portion for accommodating said jam nuts and for connecting means to a source of compressed air, the other end of said air tube reaching to a point just short of the inner edge of said threaded hole, a small amount of granulated abrasive material contained within said bag.
